UNITED STATES PATENT OFFICE.

CYRENIUS W. SILLIN, OF STUTTGART, ARKANSAS.

CHIMNEY-CAP AND STORM-SHIELD.

1,133,324.

Specification of Letters Patent. Patented Mar. 30, 1915.

Application filed March 31, 1914. Serial No. 828,604.

To all whom it may concern:

Be it known that I, CYRENIUS W. SILLIN, a citizen of the United States, residing at Stuttgart, in the county of Arkansas and 5 State of Arkansas, have invented new and useful Chimney-Caps and Storm-Shields, of which the following is a specification.

The invention relates to improvements in chimney caps and storm shields.

- 10 The object of the present invention is to improve the construction of chimney cowls and to provide a simple, practical, and comparatively inexpensive chimney cap and storm shield of strong and durable construction, adapted to be readily applied to a chimney and capable of protecting the latter from rain, snow, sleet, and wind, and adapted also to prevent downdrafts and consequent smoking of a chimney.
- 15 A further object of the invention is to provide a device of this character equipped with a rotary hood or shield, arranged to be held in the wind by a blade or vane and adapted to intercept the wind and prevent 20 the same from blowing over the chimney and choking the same.

With these and other objects in view the invention consists in the construction and novel combination of parts hereinafter fully 25 described, illustrated in the accompanying drawing, and pointed out in the claims hereto appended, it being understood that various changes in the form, size, proportions and minor details of construction, 30 within the scope of the claims, may be resorted to without departing from the spirit or sacrificing any of the advantages of the invention.

In the drawing: Figure 1 is a perspective view of a chimney cap and storm shield constructed in accordance with this invention. Fig. 2 is a central vertical sectional view of the same. Fig. 3 is a horizontal sectional view of the same. Fig. 4 is a reverse 45 plan view of the device, the bearing bracket, and the lower anchor brace being omitted. Fig. 5 is a detail view of the lower anchor brace. Fig. 6 is a detail sectional view on the line 6--6 of Fig. 2.

50 Like numerals of reference designate corresponding parts in all the figures of the drawings.

In the accompanying drawings, in which is illustrated the preferred embodiment of the invention, 1 designates a vertical shaft 55 or spindle arranged centrally of the upper portion of the chimney 2 and mounted in a bearing bracket 3 and in a lower anchor brace 4. The bearing bracket 3 comprises four legs or braces 5 consisting of lower 60 chimney engaging portions and inclined upper portions, and connected at their upper ends at the center of the bracket and supporting a bearing disk or plate 6 to which the legs or braces are suitably secured. 65

The opposite legs or braces 5 may consist of a single piece of material, as illustrated in Fig. 2 of the drawings, but the bracket may be constructed in any other suitable manner. The lower chimney engaging portions fit against the exterior of the chimney and conform to the configuration of the same, being provided at an intermediate point with angular bends to fit around the collar or projecting portion 7 of the chimney. The said angular bends of the legs 70 form intermediate horizontal portions which are arranged upon the collar 7 of the chimney, and the said legs or braces are equipped at their lower terminals with blocks or 75 pieces 9 forming shoulders for engaging beneath the collar or projecting portion 7 of the chimney. The blocks 9 are spaced from the intermediate horizontal portions 8 to receive the projecting collar or portion 7 80 of the chimney, but the lower ends of the legs or braces 5 may be provided with any other suitable means for engaging beneath the said projecting portion 7 of the chimney. The legs or braces are clamped to the chimney 85

by upper and lower set screws 10 and 11, mounted in threaded perforations and engaging the chimney. The lower set screws pierce the blocks 9 and by being located below the plane of the projecting portion 7, 90 securely fasten the bearing bracket to the upper portion of the chimney. The upper set screws assist in maintaining the bearing bracket on the chimney, but they may be omitted if desired. 95

The vertical shaft or spindle, which is rigidly supported in an upright position with relation to the chimney, has its lower terminal 12 threaded and extending through 100

a central opening in the lower anchor brace, to which the shaft or spindle is securely clamped by nuts 13 which engage the upper and lower faces of the anchor brace. The 5 anchor brace, which is horizontally disposed, is arranged interiorly of the chimney and extends diagonally across the same, and it is provided with terminal arms 14 arranged in pairs, the members of each pair 10 being disposed at right angles to each other and fitting the diagonally opposite angles of the chimney. The horizontal anchor member 4 firmly braces the lower end of the shaft or spindle and co-operates with the 15 bearing bracket in rigidly supporting the said shaft or spindle in a central vertical projecting position.

The bearing plate 6 at the apex of the bracket 3 is provided in its upper face with 20 an annular ball race 15, which receives a series of anti-friction balls 16 interposed between the fixed lower bearing plate 6, and an upper rotary bearing plate 17. The upper rotary bearing plate 17, which rests 25 upon the anti-friction balls 16, has a central opening to receive the vertical shaft or spindle, and is preferably provided at its periphery with a depending portion or flange which extends below the edge of the lower 30 bearing plate to protect the ball bearing. The upper bearing plate sustains the weight of a rotary hood or shield 18, designed to be constructed of stout galvanized sheet metal or other suitable material, and comprising 35 a horizontal top portion 19 and a depending inclined portion 20, arranged at the front of the horizontal portion and extending downwardly and outwardly therefrom to a point below the top of the chimney, and provided with a substantially vertical lower portion 21. The hood or shield, which may 40 be varied in size to suit the size of the chimney to which the device is applied, is adapted to exclude wind, snow, rain, and sleet 45 from the interior of the chimney and the front inclined portion serves to deflect the wind upwardly to cause the same to pass over the top of the device. The horizontal top portion is riveted or otherwise secured 50 to the upper face of a horizontal reinforcing plate 22, which is adapted to stiffen the horizontal top portion of the hood or shield and sustain the weight of a superimposed vane 23. The plate 22, which is constructed 55 of suitable metal, may be of any desired size, and it also preferably extends rearwardly from the inclined front portion 20 to a point in rear of the shaft or spindle. The plate 22, which has an opening to receive the upper portion, is provided with central and side rearwardly projecting arms 24, which are preferably of a length to extend to the rear edge of the horizontal top portion of the hood or shield.

60 65 The vane or blade 23, which is located

in rear of the vertical shaft or spindle 1, consists of a plate of sheet metal or other suitable material, of sufficient size to maintain the front depending portion of the hood or shield positively in the wind at all 70 times. The blade or vane, which may be of any preferred configuration, has a horizontal lower edge and is secured between upturned flanges of a pair of angle bars 25 to which the inner side edges of the horizontal side screens 26 of a spark arrester are also secured. The imperforate horizontal portion of the hood or shield is of a size to cover the opening of the chimney, so as to positively exclude moisture therefrom, and 75 the side screens 26, which extend horizontally from the rear edge of the imperforate top portion of the hood or shield, are preferably constructed of woven wire, having a mesh of a suitable size to arrest the sparks 80 to prevent the same from ascending and endangering neighboring roofs. The side screens, which are preferably tapered rearwardly, as shown, are provided at their outer edges with metallic binding strips 27, 85 and their inner edges are fitted against the faces of horizontal flanges of the angle bars 25 and are secured between the same and upper metallic bars or binding strips 28. The front edges of the spark arrester screens are 90 arranged at the upper face of the horizontal portion of the hood or shield, bound by a transversely disposed metallic strip 29 extending entirely across the hood or shield and connecting the side screens. The upturned flanges of the longitudinal angle bars 25 are cut away as shown, to provide a passage for the front transverse binding strip 29, which is arranged upon the upper face of the horizontal flanges of the said 95 angle bars 25.

The front metallic binding strip 29 is bolted or otherwise secured to the hood or shield. The side screens, which constitute the spark arrester, may be mounted in any 100 other desired manner, and the vane or blade and the side screens are braced by inclined upwardly and rearwardly diverging bars or members 30 extending from the outer portions of the side screens to the upper rear 105 portion of the blade or vane, and suitably secured to the said parts. Any other desired form of bracing may, of course, be employed.

The hood or shield is carried by a horizontally disposed rotary bar or member 31 provided at a point intermediate of its ends with an opening 32 for the shaft or spindle, and extending in advance and in rear of the same, and provided at its front end with laterally extending arms 33 set at an inclination to present inclined front faces to the inner or rear face of the depending front portion of the hood or shield. The laterally extending arms are formed by a plate or 120 125 130

piece welded or otherwise secured to the front end of the horizontal bar or member 31, and riveted or otherwise secured to the front portion of the hood or shield. The 5 rearwardly extending portion of the horizontal bar or member 31 is provided with a longitudinal kerf or slot 34, in which is secured a vertical post or support 35 constructed of sheet metal or other suitable material, bolted or otherwise secured at its 10 lower end to the rear end of the horizontal bar or member 31. The post or standard 35 extends upwardly from the horizontal bar 31 to the rear portion of the vane or blade, and its upper portion is arranged between the said vane or blade and one of the longitudinally disposed angle bars, and is secured to the vane by one or more bolts or other suitable fastening device, which 15 pierces the upturned flanges of the angle bars 25, the blade or vane, and the post. Any number of fastening devices, of course, may be employed, and the post 35, which supports the outer rear portion of the vane or blade and the outer portions of the spark 20 arrester, may be mounted in any other desired manner. The horizontal bar or member, which rests upon the upper bearing plate, is adapted to rotate freely with the 25 same, and the rotary portions of the device are retained in position on the upper projecting portion of the shaft or stem by upper and lower set collars 36 and 37, arranged at the lower face of the reinforcing 30 plate and at the upper face of the horizontal bar 31. The set collars, which are adjustable on the upper portion of the shaft or spindle, are clamped to the same by set 35 screws. The upper end 38 of the vertical shaft or spindle is threaded for the reception of the retaining nut 39, a washer being 40 preferably interposed between the same and the upper face of the horizontal portion of the hood or shield.

45 What is claimed is:

1. A device of the class described, including a supporting bracket provided with means for mounting it on a chimney at the top thereof, a vertical shaft or spindle mounted in the bearing bracket and extending above and below the same, the lower portion of the spindle being located within the chimney, an anchor brace secured to the lower end of the shaft or spindle and provided at its ends with angularly disposed edges fitting the diagonally opposite corners of the chimney, said brace being diagonally arranged within the chimney and a rotary hood or shield mounted on the upper portion 50 of the shaft or spindle.

2. A device of the class described, including a supporting bracket provided with means for mounting it on a chimney at the top thereof, a vertical shaft or spindle mounted in the bearing bracket and extend-

ing above and below the same, the lower portion of the spindle being located within the chimney, a horizontally disposed anchor brace secured to the lower end of the shaft or spindle and provided at its terminals with 70 arms arranged in pairs, the members of each pair being disposed at right angles to each other to fit the corners of the chimney, said brace being arranged diagonally in the chimney and a rotary hood or shield mounted 75 upon the upper portion of the shaft or spindle.

3. A device of the class described, including a bearing bracket comprising legs or braces having inclined upper portions connected together at their upper ends, said legs or braces being provided with lower chimney engaging portions having angular bends to rest upon the projecting portion of a chimney and provided below the bends with 80 shoulders for engaging the underside of the projecting portion of the chimney, clamping means carried by the legs or braces for engaging the chimney, a shaft or spindle supported by the bearing bracket, and a rotary 85 hood or shield mounted upon the shaft or spindle.

4. A device of the class described, including a bearing bracket comprising legs having inclined upper portions and connected at 95 their upper terminals, said legs being also provided with lower chimney engaging portions having angular bends to rest upon the projecting portion of a chimney and provided below the same with blocks adapted 100 to engage beneath the projecting portion of the chimney, clamping screws piercing the legs and the blocks for engaging the chimney, a vertical shaft or spindle supported by the bearing bracket, and a rotary hood or 105 shield mounted on the shaft or spindle.

5. A device of the class described, comprising a vertical shaft or spindle, means for securing the same to a chimney, a rotary hood or shield mounted on the shaft or spindle 110 and comprising a top portion arranged over the chimney, a vane or blade connected with the hood or shield, and a spark arresting screen carried by the hood or shield and extending rearwardly from the top portion 115 thereof.

6. A device of the class described, comprising a vertical shaft or spindle, means for securing the same to a chimney, a rotary hood or shield mounted on the shaft or spindle 120 and comprising a top portion arranged over the chimney, a vane or blade carried by the hood or shield and extending rearwardly from the top portion thereof, and spark arresting screens extending rearwardly from 125 the hood or shield and located at opposite sides of the blade or vane.

7. A device of the class described including a rotary hood or shield, means for mounting the same over a chimney, a superimposed 130

blade or vane mounted on and extending my own, I have hereto affixed my signature rearwardly from the hood or shield, and a in the presence of two witnesses. spark arresting screen extending rearwardly CYRENIUS W. SILLIN. from the hood or shield and connected with Witnesses: 5 the same and with the blade or vane. W. C. RICHARDSON, In testimony, that I claim the foregoing as HENRY F. McFADDEN.
